F. R. McGOWAN.

GAGE,

APPLICATION FILED NOV. 22, 1920.

1,380,818.

Patented June 7, 1921.

UNITED STATES PATENT OFFICE.

FRANK R. McGOWAN, OF LOWELL, MASSACHUSETTS.

GAGE.

1,380,818.

Specification of Letters Patent. Patented June 7, 1921.

Application filed November 22, 1920. Serial No. 425,900.

(FILED UNDER THE ACT OF MARCH 3, 1883, 22 STAT. L., 625.)

To all whom it may concern:

Be it known that I, FRANK ROBERT McGOWAN, a citizen of the United States, and an officer of the Government employed 5 in the Bureau of Standards, Department of Commerce, Washington, D. C., and residing at 36 Varney St., Lowell, in the county of Middlesex and State of Massachusetts, have invented a new and useful Gage, of which 10 the following is a specification.

The improvement, if patented, may be used by the Government, or any of its officers or employees in the prosecution of work for the Government or by any other person in 15 the United States without the payment of any royalty thereon.

My invention relates to improvements in a gage for determining the tautness of aeronautical fabrics; and the objects of my improvement are first to construct an instrument whose weight will not affect the ultimate readings; second, to construct an instrument that can be readily adjusted on the specimens; and third, means of supporting 20 and applying weights for the determinations.

I attain these objects by the mechanism illustrated in the accompanying drawing, in which—

30 Figure 1 is a vertical section of the entire machine; Fig. 2 a plan view of the machine; Fig. 3, a rear view of a Randall & Stickney dial showing the mechanism of the feeler with its transverse movement indicating 35 means; Fig. 4, a vertical view of three weights, F, F₁ and F₂ which are placed on plate C₆; Fig. 5, a vertical section of a part of the machine on the line 5, 5, Fig. 1.

Similar numerals refer to similar parts 40 throughout the several views.

The bar A has on its lower side near one end a singular rib a', and near the other end two longitudinal ribs a₄ a₅, the three ribs together affording a three-point support for the bar. A feeler C furnishes means whereby said feeler is mounted at the medial portion of the bar for movement transversely thereof. The movement of the indicating means is controlled by the feeler, position 45 of the feeler for maximum movement being attained by adjusting screw C₂ which is part of the convex contact point C₃ of the feeler. The lock nut C₅ tightens against the enlarged portion of the feeler C, and a disk

C₆ serves a support for weights F, F₁, F₂. 55 B is a dial for indicating the transverse movement of the feeler C through the gears b, b₂, b₃, b₅ and the pointers b₆ and b₇. The spring arm supports E E are used for holding the weight D which has an opening d₂ 60 through which the feeler passes, affording a means of interchangeable connection to either the feeler on C₄ or the support D by the special circular groove d'. The opening a₃ in the bar a is a means by which one or 65 both hands can be applied in adjusting gage in position so that the feeler C with aid of the numbers a₂ the longitudinal ribs can be placed in the center of the span.

I am aware that prior to my invention 70 dials have been made whereby the indicating means for the transverse movement of the feeler have been made. I also wish to state that no patent is requested for the indicating dial. I therefore do not claim such a 75 combination broadly.

I claim:

1. A gage for determining the tautness of aeronautical fabrics comprising a bar having on its lower side near one end a single 80 longitudinal rib and near the other end two longitudinal ribs, the three ribs together affording a three point support for the bar; a feeler, means whereby said feeler is mounted at the medial portion of the bar for 85 movement transversely thereof, movement indicating means controlled by the feeler; a weight having an opening through which the feeler passes and means whereby the weight may be connected interchangeably to 90 either the feeler or the support.

2. A gage for determining the tautness of aeronautical fabrics comprising a bar having on its lower side adjacent to its ends respectively offset contact members; a feeler, 95 means whereby said feeler is mounted at the medial portion of the bar for movement transversely thereof, movement indicating means controlled by the feeler; a fixed weight having an opening through which 100 the feeler passes and means whereby the weight may be connected interchangeably to either the feeler or the support.

3. A gage for determining the tautness of aeronautical fabrics comprising a bar having on its lower side adjacent to its ends respectively offset contact members; a feeler, 105 means whereby said feeler is mounted at the

- 2
- medial portion of the bar for movement transversely thereof, movement indicating means controlled by the feeler, the feeler having at its lower end a contact disk provided with a convex lower surface; a fixed weight having an opening through which the feeler passes and means whereby the weight may be connected interchangeably to either the feeler or the support.
- 10 4. A gage for determining the tautness of aeronautical fabrics comprising a bar having on its lower side adjacent its ends respectively offset contact members; a feeler, means whereby said feeler is mounted at the medial portion of the bar for movement transversely thereof, movement indicating means controlled by the feeler, the feeler being provided at its upper end with a weight receiving disk; a fixed weight having an opening through which the lower end of the feeler passes and means whereby the weight may be connected interchangeably to either the feeler or the support.
- 15 5. A gage for determining the tautness of aeronautical fabrics comprising a bar having on its lower side and near its ends respectively longitudinal contact ribs; a feeler, means whereby said feeler is mounted at the medial portion of the bar, movement indicating means controlled by the feeler and 30 means whereby weights may be mounted on the feeler; the bar being provided with scales adjacent its contact ribs; the graduations of the scales being numbered to correspond with the distances from the center 35 point of the bar.
6. A gage for determining the tautness of aeronautical fabrics comprising a bar having on its lower side longitudinal contact ribs; a feeler, means whereby said feeler is 40 mounted at the medial portion of the bar for movement transversely thereof, movement indicating means controlled by the feeler, the feeler including a contact member having a convex contact surface and 45 having screw-thread engagement with the lower extremity of the feeler body, whereby the contact member is adjustable with relation to said body, and means whereby weights may be mounted on the feeler.

F. R. McGOWAN.
